UNITED STATES PATENT OFFICE.

PYWELL VINCENT, OF PORTLAND, MAINE.

WINDOW-SCREEN.

1,107,385.

Specification of Letters Patent. Patented Aug. 18, 1914.

Application filed January 17, 1914. Serial No. 812,813.

To all whom it may concern:

Be it known that I, PYWELL VINCENT, a citizen of Canada, and subject of the King of Great Britain, residing at Portland, in the county of Cumberland and State of Maine, have invented certain new and useful Improvements in Window-Screens, of which the following is a specification, reference being had therein to the accompanying drawing.

This invention relates to window screens, more particularly of the slidable type, and has for its object the provision of a screen furnished with improved instrumentalities enabling the same to be readily attached to or detached from the usual window casing, and more specifically the invention comprises suitable guiding means adapted to be fixed to a window casing and devices carried by the screen having an interfitting relation with said guiding means to cause a retention or release of the screen from the window casing by a simple shifting movement of the screen with reference to the guiding means, thus dispensing with special locks or latches.

The preferred embodiment of the invention, made in keeping with the foregoing objects, includes a pair of guide flanges arranged along the side rails of a window casing, and a screen having a suitable frame adapted to bear against said flanges, associated with guiding and retaining fingers or clips carried by the screen frame adapted to slidably engage the opposite face of the flanges, the flanges being provided with open portions permitting the lateral withdrawal of the fingers or clips therethrough when brought to registering position to release the screen from the casing; and one of the clips being of a springy nature, adjustable to create a frictional engagement thereof with the guide flanges sufficient to hold the screen in adjusted positions vertically of the casing; the upper and lower edges of the fingers or clips or the upper and lower edges of the open portions of the guide flanges or both, as the case may be, being deflected or beveled slightly out of the true vertical plane of the guide flanges to normally facilitate the riding of the fingers or clips over the said open portions when the screen is in working combination with the casing, and compelling lateral forcible deflection of the screen frame to cause the passage of the clips or fingers through the openings of the guides while the screen is being removed.

I have illustrated the above mentioned embodiment of the invention in the accompanying drawings forming part hereof, and improved details in the construction and arrangement of parts will be apparent from an inspection of such drawings in connection with the specific description hereinafter contained.

In the drawings: Figure 1 is an inside view of a portion of a window casing with the screen applied thereto; Fig. 2 is an outside view of the same; Fig. 3 is a vertical sectional view through the screen frame and the guide clips carried thereby, showing the relation of the same to the guides at the sides of the window casing; Fig. 4 is a horizontal sectional view through the lower clip showing the means for adjusting the same, Fig. 5 is a vertical sectional view showing by dotted lines the various positions of the screen with reference to the guides during the removal of the screen from the casing, and Fig. 6 is a horizontal section through one side of the window casing looking down upon the top of the screen, and Fig. 7 is a detail vertical sectional view through one of the guide fingers looking toward its guide flange.

Referring more specifically to the drawings, A represents an ordinary window casing provided with the usual lower and upper sliding sashes B and C working in suitable runways formed in the casing.

D is a slidable screen formed of any suitable material conveniently wood, as shown in this instance, the same being adapted to be fitted to the window casing in an outside position relative to the sliding sashes, the window casing being provided with a suitable, improved simple type of guide to that end. These guides are constituted by single flanges E projecting outwardly at right angles from an integral flat base F screwed or otherwise secured to the projecting part ¹⁰⁰ a of the casing A, as indicated at G, the guide members thus defined being preferably formed of sheet metal. The upper rail d of the screen frame D is rabbeted at its opposite ends, as at d' to receive guide fingers or clips H secured in the rabbeted portions by devices h the rabbets being deeper at the side edges of the sash so as to leave a space e between the rail D and the projecting portion of the guide finger H ¹¹⁰ for the reception of the guide flange E. Below the clips H I provide clips or guide

fingers I secured to the side rails d^2 of the screen frame, as at i, the guide fingers or clips I being preferably arranged midway of the length of the side rails.

5 A third pair of guide fingers or clips J is secured to the bottom rail d^3 , the same being formed of spring metal and provided with slotted portions j for the reception of securing screws j' , the same as the fastening arrangement for the devices H, this method of fastening enabling longitudinal adjustment of the upper and lower fingers, and the same being formed of spring metal normally tending to spring outwardly from 10 the screen rails to which they are attached, they may be adjusted laterally of the guide rails E through the medium of the screws j' , to create a greater or less frictional binding contact with the guide rails and thus 15 secure a sufficient gripping of the rails to hold the screen in any position of vertical adjustment. The guide fingers or clips I, J, that is, the projecting portions thereof are turned or deflected outwardly at their upper and lower edges with reference to the 20 adjacent surface of the guide rails for a purpose as will presently appear.

The guide members E have respectively 25 cut-away portions or recesses K, conveniently two, one arranged near the lower end and the other adjacent the top rail of the screen when the latter is in its normal closed position, the upper and lower edges of the recessed portions being beveled or turned 30 inwardly toward the side rails of the screen frame, in other words away from the surface over which the guide fingers or clips ride, so that the clips aided by their special 35 formation will normally ride over the slotted portion of the guides so that the screen will not become detached, while at the same time the recessed portions are so arranged that the screen may be readily removed therethrough, which is accomplished by 40 raising the screen until the guide clips J register with the lowermost recesses when by an outward pressure on the screen frame the clips will be forced through to the opposite sides of the guides, and further raising 45 movement of the screen will bring the middle clips I in registration with the upper recesses, when the said middle clips are forced therethrough and the screen pulled down with the released clips behind the 50 guides until the upper clips come into registration with said upper recesses and are released therethrough, the screen frame assuming an inclined position to pass down beyond the sill of the casing to permit the 55 upper clips to move downwardly sufficiently far to pass through said upper recess. The screen is inserted by a reverse operation to that just defined. The screen frame is of course furnished with any desired screen 60 fabric L, such as the conventional wire mesh,

and all of the clips are preferably formed of metal.

From the foregoing description it will be appreciated that by simple, inexpensive means, I have provided a practical screen attachment for windows and one in which the screen may be applied or removed without the necessity for manipulating locking devices or as stated, in another way, the screen as removed is intact so far as the parts thereof are concerned and remains in the same condition when applied in the window casing without the necessity of any adjustments whatever, save only as, from time to time, it may be desirable to regulate the degree of holding friction of the lower clips through the medium of the adjustment of the outer fastening screw thereof.

While I have herein disclosed one special embodiment of the invention, it will be apparent to persons skilled in the art, that changes may be made in the construction and arrangement of parts without departing from the spirit of the invention as may be comprehended in the hereto appended claims.

Having thus described the invention, what is claimed is:—

1. The combination with a window casing, of guide plates thereon having open portions, and a screen associated with said guide plates, the screen having fingers on one face thereof constructed and arranged to be inserted through said open portions and to embrace the said guide plates between the same and the adjacent face of the screen frame.

2. The combination with a window casing, of guides thereon having open portions, and a screen associated with said guides having guide fingers on one surface thereof adapted to be inserted through said open portions to embrace the guides between the same and the adjacent faces of the screen frame, the guide fingers being turned at the upper edges thereof in a direction away from the guides.

3. The combination with a window casing, of guides thereon having open portions, and a screen associated with said guides having guide fingers on one surface thereof adapted to be inserted through said open portions to embrace the guides between the same and the adjacent faces of the screen frame, the guide fingers being turned at the upper and lower edges thereof in a direction away from the guides.

4. The combination with a window casing, of guides thereon having open portions, and a screen associated with said guides having guide fingers on one surface thereof adapted to be inserted through said open portions to embrace the guides between the same and the adjacent faces of the screen frame, the upper edges of the open portions

of the guides being turned in a direction away from the guide fingers.

5. The combination with a window casing, of guides thereon having open portions, 5 and a screen associated with said guides having guide fingers on one surface thereof adapted to be inserted through said open portions to embrace the guides between the same and the adjacent faces of the screen 10 frame, the upper and lower edges of the open portions of the guides being turned in a direction away from the guide fingers.

6. The combination with a window casing, of guides thereon having open portions, and a screen associated with said guides having guide fingers on one surface thereof adapted to be inserted through said open portions to embrace the guides between the same and the adjacent faces of the screen frame, the guide fingers being turned at the upper edges thereof in a direction away from the guides, and the corresponding upper edges of the open portions of the guides being turned in a direction away from the guide fingers.

7. The combination with a window casting, of guides thereon having open portions, and a screen associated with said guides having guide fingers on one surface thereof

[30] adapted to be inserted through said open portions to embrace the guides between the same and the adjacent faces of the screen frame, the guide fingers being turned at the upper and lower edges thereof in a direction away from the guides, and the corresponding upper and lower edges of the open portions of the guides being turned in a direction away from the guide fingers.

[35]

140 8. The combination with a window casement, of guides thereon comprising base flanges and single guide flanges projecting outwardly therefrom and having open portions, and a screen associated with said guides having guide fingers on one surface thereof adapted to be inserted through said open portions to embrace the guides between the same and the adjacent faces of the screen frame, substantially as described.

9. The combination with a window casting, of guides thereon having open portions, and a screen associated with said guides having guide fingers on one surface thereof adapted to be inserted through said open portions to embrace the guides between the same and the adjacent faces of the screen frame, the guide fingers and open portions being relatively arranged to permit removal of the screen with all of its parts normally intact.

60 10. The combination with a window
casing, of guides thereon comprising base
flanges and single guide flanges projecting
outwardly therefrom and having open por-
tions, and a screen associated with said
65 guides having guide fingers on one surface

thereof adapted to be inserted through said open portions to embrace the guides between the same and the adjacent faces of the screen frame, the guide fingers and open portions being relatively arranged to permit removal of the screen with all of its parts normally intact. 70

11. The combination with a window casing, of guides thereon having open portions, a screen associated with said guides having guide fingers on one surface thereof adapted to be inserted through said open portions to embrace the guides between the same and the adjacent faces of the screen frame, and means for adjusting one of the guide fingers to cause the same to frictionally engage a surface of the adjacent guide, substantially as described. 75 80

12. The combination with a window casing, of guides thereon comprising base flanges and single guide flanges projecting outwardly therefrom and having open portions, a screen associated with said guides having guide fingers on one surface thereof adapted to be inserted through said open portions to embrace the guides between the same and the adjacent faces of the screen frame, and means for adjusting one of the guide fingers to cause the same to frictionally engage a surface of the adjacent guide, substantially as described. 85 90 95

13. The combination with a window casing, of guides thereon having spaced open portions, and a screen associated with said guides having guide fingers on one surface thereof, one above and another below the spaced open portions, adapted to be inserted through said open portions to embrace the guides between the same and the adjacent faces of the screen frame, substantially as described. 100 105

14. The combination with a window casing, of guides thereon comprising base flanges and single guide flanges projecting outwardly therefrom and having spaced open portions, and a screen associated with said guides having guide fingers on one surface thereof, one above and another below the spaced open portions, adapted to be inserted through said open portions to embrace the guides between the same and the adjacent faces of the screen frame, substantially as described. 110 115

15. The combination with a window casing, of guides thereon having spaced open portions, and a screen associated with said guides having guide fingers on one surface thereof, one above, one below and another between the spaced open portions, adapted to be inserted through said open portions to embrace the guides between the same and the adjacent faces of the screen frame, substantially as described. 120 125

16. The combination with a window casing, of guides thereon comprising base 130

flanges and single guide flanges projecting outwardly therefrom and having spaced open portions, and a screen associated with said guides having guide fingers on one surface thereof, one above, one below and another between the spaced open portions, adapted to be inserted through said open portions to embrace the guides between the

same and the adjacent faces of the screen frame, substantially as described.

10

In testimony whereof I hereunto affix my signature in the presence of two witnesses.
